UNITED STATES PATENT OFFICE.

RICHARD S. JACOBSEN, OF CHICAGO, ILLINOIS, ASSIGNOR TO JACOBSEN & SCHRAEDER, INCORPORATED, OF CHICAGO, ILLINOIS, A CORPORATION.

MEANS FOR OPERATING RECIPROCATING CONVEYERS OR SCREENS.

1,386,505.

Specification of Letters Patent. Patented Aug. 2, 1921.

Application filed September 11, 1916. Serial No. 119,554.

To all whom it may concern:

Be it known that I, RICHARD S. JACOBSEN, a subject of the King of Norway, residing in the city of Chicago, county of Cook, and 5 State of Illinois, have invented certain new and useful Improvements in Means for Operating Reciprocating Conveyers or Screens, of which the following is a specification.

This invention relates to a novel mechanism for driving conveyers or screens with a reciprocating motion wherein the forward and backward strokes of each revolution, respectively, progressively increase and diminish in speed for the greater part of their 15 travel. That is, this progressive acceleration or retardation is applied to approximately two-thirds of the stroke, the last third being utilized in reversing and thereby reducing the shock which would occur 20 in a sudden reversal.

Much time and study has been devoted to the reduction or elimination of this reaction or shock due to the reversal at the end of the strokes and as a result, heavy, expensive and complicated mechanisms have 25 been devised, and in some cases heavy fly wheels and massive foundations were provided. In all of these instances, the costly mechanisms and supporting structures 30 would not permit the use of the same for conveying purposes, and in many installations the mechanisms were fractured due to such shock or slight deviation from the essential alinement of shafts or other parts. 35 It is therefore, an object of this invention to overcome these disadvantages and to produce a mechanism of such character that will combine efficiency and simplicity, and one that shall be low in original cost and 40 maintenance to permit the adoption of the same for conveying purposes.

Among other objects and advantages are the following:

First: The conveying trough can be made 45 in two sections actuated by mechanisms mounted on a single drive shaft, such mechanisms being arranged on said shaft in such manner that the momentum of the trough sections will be counter-balanced, thereby 50 reducing the reaction to a minimum, and permitting the use of a lighter supporting structure or foundation at greatly reduced cost.

Second: With this apparatus, the material 55 can be conveyed forward on one trough and

in reverse direction on the other trough, by arranging the troughs in stepped relation, one above the other and mounting their driving mechanisms in opposite relative positions on the common drive shaft, thereby 60 adapting this apparatus to screening and grading.

Third: A number of driving eccentrics can be mounted on and actuated by a common drive shaft.

Fourth: The driving shaft receives its impulse centrally and directly on the center line of the power driven pulley which eliminates any twisting effect.

Fifth: The connecting pins for the link 70 between the pulley and crank-arms are supported at both ends and are therefore in double shear which affords desirable strength.

To these and other objects my invention 75 consists in the novel construction, combination, association and relative position of parts and members set forth in the following specification and accompanying drawings, and more particularly brought out in 80 the appended claims.

This particular motion may be obtained and imparted to the conveying trough or screen through the herein illustrated construction and arrangement which is one embodiment of my invention and which includes connecting rods extending from ordinary eccentric disks mounted on a non-uniformly rotating shaft carried eccentrically with relation to the center of the 90 two supporting bearings which also support the power driven pulley eccentrically to said shaft and which shaft has operative connection with said pulley by means of a crank arm rigidly mounted thereon and a 95 link connecting the same to the pulley.

Referring to the drawings in which like reference characters indicate like or corresponding parts, Figure 1 is a sectional elevation of a mechanism embodying my invention taken on line 1-1 of Fig. 2, and showing the connection to a pair of conveyers or screens partly shown. Fig. 2 is a half plan of Fig. 1; the conveyers or screens and mechanism being symmetrical 105 about the longitudinal center line. Fig. 3 is a section taken on line 3-3 of Fig. 4, illustrating the power driven pulley and its connection to the non-uniformly rotating shaft. Fig. 4 is a sectional view taken on 110

line 4—4 of Fig. 3, illustrating the pulley, drive shaft, supporting bearings, crank arm and connecting link. Fig. 5 is a view taken on line 5—5 of Fig. 3 showing the link connecting pins in double shear.

Referring to the drawings, I provide a pair of conveyer troughs 30 and 31 mounted in stepped relation, the lower trough adapted if desired, to receive material from the above trough 30. As indicated on the drawings, the upper trough 30 conveys material in a forward direction and the lower trough 31 in an opposite or backward direction, thus especially adapting this arrangement to the grading of granular materials such as coal, stone, and the like. The reciprocating troughs are mounted on rollers 32 or their equivalent, and have pivotal connection with connecting rods 33 extending from the sides thereof to ordinary eccentrics 34 and 35 which are oppositely mounted on the non-uniformly rotating shaft 36 which imparts or transmits to the same the progressively accelerating and retarding motion respectively, for the greater part of each forward and backward stroke.

It will be observed that the shaft 36 is supported at the ends by a pair of ordinary bearings 37 and intermediately by a pair of special eccentric bearings 38 and 39 which support the shaft 36 eccentrically with relation to the center of the over-hanging mountings 38^A and 39^A upon which are loosely mounted the divided hub portions 40^B and 40^C of the power-driven pulley 40. Any number of spokes 40^A may be provided and arranged in two sets as indicated in Figs. 4 and 5, one set extending from each hub portion to the pulley rim 40^D. Centrally mounted with respect to the pulley and shaft (indicated in views 4 and 5) is the crank arm 41 which is keyed to the shaft 36 and which has operative connection with the pulley 40 through the cast steel link 42 and pins 43 and 44. The steel link 42 includes the sleeve 42^A and a pair of parallelly disposed integral arms 42^B.

Attention is directed to the following:

First: The pins 43 and 44 which connect the cast link 42 with the crank arm 41 and the pair of spokes 40^A, are in double shear.

Second: The center of revolution of the uniformly rotating power-driven pulley 40 is placed to one side of the center of shaft 36 which rotates with progressive acceleration and retardation respectively for the greater part of each forward and backward stroke of the connecting rods.

Third: The mechanism is symmetrical about the longitudinal center line of the troughs. It will be understood that to convert the conveyer troughs into screens it is only necessary to perforate the bottom plates as shown dotted and that in both cases the

lineal speed with a comparatively quick reverse is imparted toward the end of each forward stroke whereby the material is advanced while the trough is drawn beneath in the opposite direction.

While I have shown and described in detail the exact manner in which I prefer to carry out my invention and have illustrated and described a specific apparatus adapted to perform the results aimed at by my invention in the simplest manner, it is to be understood that I do not regard my invention as limited to these details of operation or construction, or mechanical equivalents, except in so far as they are included within the terms of the following claims, in which it is my intention to claim all novelty inherent in the invention in as broad a manner as is permissible in view of the prior art.

The two bearings 39^A and 38^A are oppositely disposed and axially alined and spaced apart a distance to accommodate the crank arm 41 between them on the shaft, in the manner explained. The eccentrics 34 and 35 are each composed, as shown, of an eccentric cam on the shaft and a strap on each cam, together with a reciprocating pitman 33 for each eccentric strap, so that each pitman is reciprocated positively in opposite directions by its allotted eccentric cam on the shaft. The horizontally disposed conveyers 30 and 31, as is well known, have what may be called a reverse motion conveying action, and are operated in this manner in a very positive and reliable way by the eccentrics on the shaft 36, which latter and the rotary driving member 40 are mounted, as shown and described, to rotate about parallel axes, with a connection from the rotary member to the shaft, so that the constant speed rotation of the pulley or rotary member is converted into a variable speed rotation on the part of said shaft. Shaft 36 is eccentrically mounted to rotate in the bearings 38^A and 39^A, so that the axis of said shaft is fixed relatively to the parallel axis of the pulley, and the distance between these two axes will depend, of course, upon the exact character of the motion required for operating the conveyers.

I claim:

1. Means for operating reciprocating conveyers or screens, comprising in combination, a pair of bearings, a uniformly rotating power-driven pulley centrally mounted on said bearings, a non-uniformly rotating shaft extending through said bearings and through said pulley and to one side of the axis of revolution of the same, and connecting means for said pulley and shaft, transmitting to said shaft a motion substantially as described.

2. Means for operating reciprocating conveyers or screens, including in combination a pair of bearings, a uniformly rotating power-driven pulley centrally mounted on

said bearings, a non-uniformly rotating shaft extending through said bearings and through said pulley and to one side of the axis of revolution of the same, and connecting means arranged between said bearings for said pulley and shaft comprising a crank arm and link for transmitting to said shaft a motion substantially as described. 5

3. The combination in a mechanism for 10 operating reciprocating conveyers, of a uniformly rotating power-driven pulley, a pair of bearings supporting said pulley, a shaft, and means arranged between said bearings and operated by said pulley for transmitting to said shaft a non-uniform motion substantially as described, said means being centrally mounted with relation to said pulley. 15

4. The combination in a mechanism for 20 operating reciprocating conveyers, of a uniformly rotating power-driven pulley, a shaft, means operated by said pulley for transmitting to said shaft a non-uniform motion substantially as described, a plurality of pairs of oppositely mounted eccentrics mounted on said shaft and arranged symmetrically about said pulley, and operating members connected to said eccentrics. 25

5. The combination in a mechanism for 30 operating reciprocating conveyers, of a uniformly rotating power-driven pulley, a pair of bearings supporting said pulley, a single straight shaft extending through said bearings and through said pulley and to one side 35 of the axis of revolution of the same, and means for transmitting to said shaft a non-uniform motion substantially as described including an arm rigid with said shaft mounted between said bearings, and means 40 operatively engaging said arm with said pulley.

6. The combination in a mechanism for 45 operating reciprocating conveyers, of a uniformly rotating power-driven pulley having a divided hub, a straight shaft extending within the plane bounded by the circumference of said pulley and to one side of the axis of revolution of the same, a pair of bearings for supporting said pulley divided 50 hub eccentrically to said shaft, said shaft extending into said bearings, and means for transmitting to said shaft a non-uniform motion substantially as described, including an arm rigid with said shaft and mounted 55 between said divided hub, and means operatively connecting said arm with said pulley.

7. The combination in a mechanism for 60 operating reciprocating conveyers, of a uniformly rotating power-driven pulley having a divided hub, a straight shaft extending within the plane bounded by the circumference of said pulley and to one side of the axis of revolution of the same, a pair of bearings for supporting said pulley hub 65 eccentrically to said shaft, said shaft ex-

tending through said bearings, and means for transmitting to said shaft a non-uniform motion substantially as described, including an arm rigid with said shaft and mounted between said divided hub, means 70 operatively connecting said arm with said pulley, a plurality of eccentrics mounted on said shaft, and operating members connected to said pairs of oppositely mounted eccentrics. 75

8. The combination in a mechanism for 75 operating reciprocating conveyers, of a uniformly rotating power-driven pulley having a divided hub, a single straight shaft extending through said pulley and to one side of the axis of revolution of the same, a pair of bearings supporting said hub and means for transmitting to said shaft a non-uniform motion substantially as described including an arm rigid with said shaft and 80 mounted between said bearings, means operatively connecting said arm with said pulley, a plurality of eccentrics mounted on said shaft, and operating members connected to said eccentrics. 85

9. The combination in a mechanism for 90 operating reciprocating conveyers or screens, of a uniformly rotating pulley having a divided hub; a plurality of bearings supporting said hub; a shaft supported in said bearings and extending through said pulley eccentrically to the axis of revolution of the same; and means for transmitting to said shaft a non-uniform motion comprising an arm rigid with said shaft and mounted between said bearings, a link, and a pair of pins connecting said link with said pulley and arm, said pins being in double shear. 95

10. The combination in a mechanism for 100 operating reciprocating conveyers or screens, of a pulley having a hub divided in two portions and a set of spokes extending between each of said portions and the pulley rim; a pair of bearings supporting said portions; a shaft supported in said bearings 105 and extending through said hub portions eccentrically to the axis thereof; and means for transmitting to said shaft a non-uniform motion comprising an arm rigid with said shaft and mounted between said bearings, a link extending between a pair of spokes and having a forked extension embracing said lever, and means connecting said link with said spokes and lever. 110

11. A mechanism for operating reciprocating troughs and in combination, a shaft; a pair of bearings for said shaft; a pulley having a divided hub mounted on said bearings eccentrically to said shaft; and means for transmitting a non-uniform motion to 115 said shaft comprising an arm rigid with said shaft and mounted between said bearings, a forked link extending between said pulley and arm and connection pins in double shear connecting said pulley with said arm. 120

12. The combination in a mechanism for 5
operating reciprocating conveyers or screens, 10
of a uniformly rotating pulley; a bearing
supporting said pulley; a shaft supported
in said bearing and extending through said
pulley eccentrically to the axis of revolution
of the same; and means for transmitting to
said shaft a non-uniform motion comprising
an arm rigid with said shaft, a link, and a
pair of pins connecting said link with said
pulley and arm, said pins being in double
shear.
13. The combination in a mechanism for 15
operating reciprocating conveyers, of a uni-
formly rotating power-driven pulley, a shaft,
means operated by said pulley for trans-
mitting to said shaft a non-uniform motion
substantially as described, a plurality of
pairs of eccentrics mounted on said shaft
20 and arranged symmetrically about the cen-
ter line of the conveyer, and operating mem-
bers connected to said eccentrics.
14. The combination in a mechanism for 25
operating reciprocating conveyers, of a single
shaft, a uniformly rotating power-
driven pulley mounted eccentrically with
relation to said shaft, means operated by
said pulley for transmitting to said shaft
a non-uniform motion substantially as de-
30 scribed, a pair of eccentrics mounted on said
shaft and arranged symmetrically about the
center line of the conveyer, and operating
members connected to said eccentrics.
15. The combination in a mechanism for 35
operating reciprocating conveyers, of a uni-
formly rotating power-driven pulley, a shaft,
means operated by said pulley for trans-
mitting to said shaft a non-uniform motion
substantially as described, eccentrics
40 mounted on said shaft and arranged sym-
metrically about the center line of the con-
veyer, and operating members connected
to said eccentrics.
16. The combination, in a mechanism for 45
operating reciprocating conveyers, of a uni-
formly rotating pulley, a plurality of oppo-
sitely mounted eccentrics arranged sym-
metrically with relation to the conveyer, and
interconnecting means between said pulley
50 and said eccentrics for transmitting to said
eccentrics a non-uniform motion substan-
tially as described.
17. The combination in a mechanism for 55
operating reciprocating conveyers, of a uni-
formly rotating pulley, a plurality of eccen-
trics mounted symmetrically with relation to
the conveyer, and interconnecting means be-
- tween said pulley and said eccentrics for
transmitting to said eccentrics a non-uniform
motion substantially as described. 60
18. The combination in a mechanism for
operating reciprocating conveyers, of a uni-
formly rotating pulley, an eccentric mecha-
nism mounted symmetrically with relation
from above and interconnecting means op-
erated by said pulley for transmitting to
said eccentric mechanism a non-uniform mo-
tion, substantially as described. 65
19. The combination in a mechanism for 70
operating reciprocating conveyers, of a uni-
formly rotating pulley, a plurality of eccen-
trics for actuating the conveyers, and inter-
connecting means between said pulley and
said eccentrics for transmitting to said 75
eccentrics a non-uniform motion, substan-
tially as described.
20. The combination of a pair of hori-
zontally disposed reciprocating conveyer 80
troughs having reverse motion conveying
action, and a driving mechanism therefor
including a single shaft driven with a non-
uniform motion, and eccentrics on said shaft
for driving said troughs.
21. The combination of a pair of hori-
zontally disposed reciprocating conveyer 85
troughs having reverse motion conveying
action, and a driving mechanism therefor
including a uniformly rotating pulley, a shaft
driven with a non-uniform motion, and 90
eccentrics on said shaft operatively con-
nected to said troughs.
22. The combination of a rotary driving
member, a shaft, means for supporting said 95
member and shaft for rotation about par-
allel and relatively fixed axes, a crank arm
on the shaft, and a link to connect said mem-
ber to the end of said arm.
23. The combination of a pair of oppo-
sitely disposed and axially alined stationary 100
cylindric bearings spaced apart a distance,
a shaft eccentrically mounted to rotate in
said bearings, a driving member mounted
to rotate on said bearings, and a connection
from said member to the shaft between said 105
bearings.
24. A structure as specified in claim 23,
in combination with eccentrics mounted on
the shaft outside of said bearings.
- In witness whereof, I have hereunto sub- 110
scribed my name this 1st day of Septem-
ber, 1916.

RICHARD S. JACOBSEN.
